Primary Examiner — Cathy A MacCormac(74) *Attorney, Agent, or Firm* — Flynn, Thiel, Boutell & Tanis, P.C.**CLAIM**

The ornamental design for a combined printer, copy machine, scanner and fax machine, as shown and described.

DESCRIPTION

FIG. 1 is a top front perspective view of a combined printer, copy machine, scanner and fax machine showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
